UNITED STATES PATENT OFFICE.

CHARLES F. DODGE, OF POCOHONTAS, ILLINOIS.

CAR-STARTER.

SPECIFICATION forming part of Letters Patent No. 315,258, dated April 7, 1885.

Application filed September 19, 1884. (No model.)

To all whom it may concern:

Be it known that I, CHARLES F. DODGE, of Pocahontas, in the county of Bond and State of Illinois, have invented a certain new and 5 useful Improvement in Car-Starters, of which the following is a specification.

The improvement relates to apparatus for starting cars, more particularly horse-cars, and is designed to relieve the strain upon the 10 horses which is incident to starting such cars.

I will describe in detail a car embodying my improvement, and then point out the novel features in claim.

In the accompanying drawings, Figure 1 is 15 a plan of a car-truck embodying my improvement. Fig. 2 is a side elevation thereof, and Fig. 3 is a detail view showing the operation of certain parts, a portion being broken away.

Similar letters of reference designate corresponding parts in all the figures.

A A' designate wheels secured in the usual or any other suitable manner to axles B. Said axles have their bearings in suitable journal-boxes, a. Ratchet-wheels a' are secured, by 25 bolts or otherwise, to the inner sides of the wheels A. I prefer that the peripheries of the ratchet-wheels a' shall be approximately flush with the "tread" of the car-wheels, or portions thereof adapted to bear upon the tops 30 of the rails.

C designates side pieces of the truck-frame, which, as shown, are secured together by transoms D D'. Said truck-frame is adapted to be supported upon the journal-boxes in the 35 usual or any other suitable manner. The car-body is preferably secured to stanchions b on stringers or side pieces, c, extending lengthwise of the truck-frame and rigidly affixed thereto by bolts or otherwise. Said stanchions 40 and side pieces may be made of wood or metal.

F designates standards, which I prefer to arrange upon the outwardly-extending ends 45 of the side pieces, C. Said standards are firmly affixed to said side pieces by means of bolts, screws, or otherwise, and extend for a considerable distance above said side pieces. Near the upwardly-extending end of the standards F are apertures forming slideways, in 50 which may slide freely slider-bars G. Rods H H' connect the slider-bars in such manner that when said slider-bars are moved back-

ward and forward they will act in unison. The forward and backward excursion of said slider-bars is limited by the bars H H' coming in contact with the stanchions F. Upon the 55 outer side of the slider-bars G, I preferably arrange plates I. Near one end the plates I are recessed to receive the circular portions of pawls J. Apertures in the pawls J are adapted to receive pins f on the slider-bars 60 G. The pins f fit loosely in the apertures of the pawls in such manner that the said pawls may turn freely about said pins. The normal position of the pawls J is such that the free ends thereof extend downwardly at an angle 65 in the direction of the rotation of the wheel when the car is moving forward, which position they assume by gravity, being prevented from attaining a vertical position by pins g, also rigidly secured to the slider-bars G. 70 When the said slider-bars are moved forward, the pawls J engage with the ratchet-wheels a' on the wheels A, and cause the same to rotate. When, however, the slider-bars are moved backward, the pawls J slide freely over the 75 teeth on said ratchet-wheels.

In Fig. 3 I have best shown a plate, K, which is secured to the plates I by screws or otherwise. Said plate K protects the pawls J and prevents their becoming detached from the 80 pins f. Obviously the plate K may be omitted and its purpose fulfilled by downwardly-extending portions on the plates I. The pawls J are arranged so close together that at least two of them are at all times in engagement 85 with the teeth on the ratchet-wheel a', and by arranging them upon an incline, as previously described, the strain upon the pawls is partly borne by the pins g, and the liability of breakage occurring at the pins f is thereby lessened. 90

L is a rod extending in the direction of the length of the truck-frame, and arranged about midway between the side pieces, C. Said rod extends through apertures in the transoms D D', and is adapted to move freely backward 95 and forward therein. I have shown an adjustable collar, i, arranged upon the rod L, near one end thereof, and secured thereto by means of a set-screw, i', by which means the position of the collar may be varied. Said collar is adapted to limit the backward excursion of the rod L. A hook, j, on the end of

the rod L is intended to afford a means of attaching a whiffletree to the said rod.

At a point between the transoms D D', I secure another collar, M, to the rod L by means 5 of a set-screw, k. Secured to the collar M by nuts or otherwise, and extending in a direction opposite to that of the arrow shown in Fig. 1, is one of the ends of rods N. The other ends of the rods N are rigidly secured 10 by nuts or otherwise to the rod H'.

It is obvious that when the rod L is moved forward it will by means of its connection with the slider-bars G through the rods N and the rod H' cause the said slider-bars to follow it 15 in its forward movement.

Arranged about the rod L near its rearward end is a coil-spring, O, one end of which said spring is secured to a plate, l, affixed to the inner side of the transom D by bolts or otherwise. The other end of said spring is made 20 fast to an adjustable collar, P, on the rod L. I may use the spring in other ways, and I may indeed employ springs of other kinds. Said collar P may be secured to the rod L by means 25 of a set-screw, m. The tendency of the spring is always to return the carrier-bars G to their rearmost position, and consequently the pawls J beyond their point of engagement with the ratchet-wheels a'. When the rod L is pulled 30 forward, it carries with it the carrier-bars G and the pawls J. The pawls J will then successively come into engagement with the teeth on the ratchet-wheels a', thereby causing the 35 wheel A to rotate and the car to start its forward movement. In thus moving forward the collar M or a shoulder on the rod L comes in contact with a transom or cross-bar of the

truck-frame. After this the car may be drawn along just as though the rod L were rigidly secured to the truck-frame. When the car 40 is stopped and the strain removed from the rod L, the latter is by the action of the spring O moved backward, carrying with it the slider-bars G and the pawls J, and the latter are again brought into position to be moved forward into engagement with the ratchet-wheels a' to start the car. I do not limit myself to the use of any particular number of pawls, as the same may be varied.

This device is very simple and effective. 50 By its use the most heavily-loaded car can be easily started.

What I claim as my invention, and desire to secure by Letters Patent, is—

In a car-starter, the combination of slider-bars moved in one direction by the motive agent of the car, a spring for moving said slider-bars in the opposite direction, car-wheels, ratchet-wheels arranged upon the car-wheels in such position that the peripheries 60 of the ratchet-wheels will be approximately flush with the portions of the car-wheels which are adapted to bear upon the top of the rails, pawls arranged upon the slider-bars at an incline in the direction of the rotation of the 65 wheel when the car is moving forward, and in such manner that at least two of them will engage with the teeth of a ratchet-wheel to rotate the car-wheel, substantially as specified.

CHAS. F. DODGE.
